E. MILES.

MATERNITY GOWN.

APPLICATION FILED AUG. 30, 1912.

1,067,537.

Patented July 15, 1913.

UNITED STATES PATENT OFFICE.

ELIZABETH MILES, OF EVANSTON, ILLINOIS.

MATERNITY-GOWN.

1,067,537.

Specification of Letters Patent. Patented July 15, 1913.

Application filed August 30, 1912. Serial No. 717,865.

To all whom it may concern:

Be it known that I, ELIZABETH MILES, a citizen of the United States, and a resident of the city of Evanston, county of Cook, 5 and State of Illinois, have invented certain new and useful Improvements in Maternity-Gowns, of which the following is a specification.

My invention relates to improvements in 10 maternity gowns and has for its object the production of a gown of this character which will allow of expansion at the waist-line, bust and abdomen sufficient to meet the physical requirements at all periods without 15 the length of the garment visibly altering during development.

A further object is the production of a 20 gown as mentioned which will be simple and economical in construction, one which will afford great comfort when worn and one which will be of neat and finished appearance.

Other objects will appear hereinafter.

The invention consists in the combinations 25 and arrangements of parts hereinafter fully described and claimed.

The invention will be best understood by reference to the accompanying drawings forming a part of this specification and in 30 which,

Figure 1 is a front view of a gown embodying my invention, and Figs. 2, 3 and 4 are enlarged fragmentary sections taken on substantially lines $x-x$, $y-y$ and $z-z$, respectively, of Fig. 1.

The preferred form of construction as illustrated in the drawing comprises a gown consisting of a body 1 in which the waist and skirt portions are formed integral. Said 40 body 1, except at the front, is of ordinary construction, the same being provided with sleeves 2 and with a conventional collar or other suitable trimming 3. The front side of the body 1 is open, the front edges overlapping as clearly shown in the several views. Provided at said overlapping edges are panels 4 and 5 which extend the entire 45 length of the gown, the same being formed by lines of stitching 6 and 7, respectively, 50 which pass through the turned-back or folded portions of the garment as clearly shown in the several views. Formed at the juncture of each of said panels with the body of the garment is an invisible plait 8, 55 the upper and lower end portions of the plait 8 being tacked by means of stitching

6 and 7 which extends therethrough at the upper and lower end portions of the garment, as shown in Fig. 3. The central portions of said plaits 8, that is the portions 60 thereof between points A and B and A' and B', are untacked, as clearly shown in Figs. 2 and 4, so as to permit of circumferential expansion of the gown at the waist-line, bust and abdomen of the wearer. Said untacked 65 portions of said plaits are bellied inwardly, that is the width of said plait portions gradually increases toward the centers thereof so that the greatest expansion will be permitted at the abdominal or waist portion 70 of the gown.

The waist of the garment is held snugly about the waist of the wearer by means of an adjustable belt 9, one end of which is connected with an eye or loop 10 provided at 75 the outer edge of panel 5, said belt passing through a slit 11 provided in the adjacent plait 8 close to the stitching 6, the same encircling the waist of the garment and having its free end engaged with a toothed loop 80 or fastening buckle 12 provided at the outer edge of the panel 4. A slide buckle 13 is provided in said belt engaging with the first mentioned end thereof which permits of extension or contraction of the belt as desired. 85 With this arrangement it will be seen that the gown may be drawn snugly around the waist of the wearer irrespective of the size thereof.

The lower end portions of the panels 4 90 and 5 are held in overlapping relation by means of ball-and-socket clasps, the socket portions 14 being provided upon panel 4 and the ball portions 15 upon panel 5. An additional set of socket portions 14' is provided upon panel 4 in order to permit of adjustment of the relative position of said 95 panels in case of abnormal development in the wearer.

With a construction as set forth it will 100 be seen that the panels of the garment, irrespective of expansion at the waist-line of the latter, will remain constantly in the same relative position and so that the alteration or expansion of the garment at the 105 waist-line, bust or abdomen will not be visible.

A garment of the construction set forth is of artistic design, correct in lines and simple in construction. The same is practical, is suitable to any material, and can be 110 styled to conform to prevailing fashion

without a suspicion of its real merit or purpose so as to enable a woman to appear at all times without calling attention to her condition, and, after its mission has been 5 fulfilled, the same is still available for general wear.

While I have illustrated and described the preferred form of construction for carrying my invention into effect, this is capable of 10 variation and modification without departing from the spirit of the invention. I, therefore, do not wish to be limited to the exact details of construction as set forth, but desire to avail myself of such variations 15 and modifications as come within the scope of the appended claims.

Having described my invention, what I claim as new and desire to secure by Letters Patent is:

20 1. A gown of the character described comprising a body consisting of integral waist and skirt portions, the front of said body being open, the front edges of said body overlapping; panels provided at said 25 edges of said body; and invisible plaits provided at the inner edges of said panels, the central portions of said plaits being untacked to permit of circumferential expansion of said body at the central portion thereof; and a 30 belt for adjustably holding said panels in overlapping relation, substantially as described and having its free end secured to the outer edges of said panels. 35

2. A gown of the character described comprising a body consisting of integral waist and skirt portions, the front of said body being open, the front edges of said body overlapping; panels provided at said edges of said body; invisible plaits provided at the inner edges of said panels, the central portions of said plaits being untacked to permit of circumferential expansion of said body at the central portion thereof; and an 40 adjustable belt encircling said body, substantially as described and having its free ends secured to the outer edges for holding said panels in overlapping relation. 45

3. A gown of the character described comprising a body consisting of integral waist and skirt portions, the front of said body being open, the front edges of said body overlapping; panels provided at said edges 50 of said body; invisible plaits provided at the inner edges of said panels, the central portions of said plaits being untacked to permit of circumferential expansion of said body at the central portion thereof; and a 55 belt for adjustably holding said panels in overlapping relation, substantially as described and having its free end secured to the outer edges of said panels.

In testimony whereof I have signed my 60 name to this specification in the presence of two subscribing witnesses.

ELIZABETH MILES.
